UNITED STATES PATENT OFFICE.

ALEKSANDER SOKOŁOWSKI, OF PERU, ILLINOIS.

DESIGN FOR A STOVE.

53,717.

Specification for Design. Patented Aug. 19, 1919.

Application filed March 14, 1919. Serial No. 282,757. Term of patent 3½ years.

To all whom it may concern:

Be it known that I, ALEKSANDER SOKOŁOWSKI, a citizen of Poland, residing at Peru, in the county of La Salle and State of Illinois, have invented a new, original, and ornamental Design for Stoves, of which the following is a specification, reference being had to the accompanying drawing, forming a part thereof.

The figure is a perspective view of a stove, showing my new design.

I claim:

The ornamental design for a stove, as shown.

ALEKSANDER SOKOŁOWSKI.
